US0D1044142S

(12) **United States Design Patent** (10) **Patent No.:** **US D1,044,142 S**
(45) **Date of Patent:** **** Sep. 24, 2024**

(54) **GLOVE**

(71) Applicant: **THE HILLMAN GROUP, INC.**,
Cincinnati, OH (US)

(72) Inventors: **Christopher Matthew Weed**,
Kennesaw, GA (US); **James Blake Fievet**, Decatur, GA (US)

(73) Assignee: **THE HILLMAN GROUP, INC.**,
Forest Park, OH (US)

(**) Term: **15 Years**

(21) Appl. No.: **29/826,104**

(22) Filed: **Feb. 9, 2022**

(51) **LOC (14) Cl.** **02-06**

(52) **U.S. Cl.** USPC **D29/117.1**

(57) **CLAIM**

The ornamental design for a glove, as shown and described.

DESCRIPTION

FIG. 1 is a dorsal side perspective view of a glove;
FIG. 2 is front elevation view of the glove;
FIG. 3 is a rear elevation view of the glove;
FIG. 4 is a side elevation view of the glove;
FIG. 5 is another side elevation view of the glove; and,
FIG. 6 is a dorsal side top plan view of the glove.
The broken lines shown in the figures represent portions of
the glove that form no part of the claimed design. The palm
side of the glove forms no part of the claimed design.

1 Claim, 4 Drawing Sheets
